HIGH-SPEED TAPE-HANDLING MECHANISM

John E. De Turk, Cambridge, and John H. MacNeill, Stoughton, Mass., assignors to Raytheon Manufacturing Company, Newton, Mass., a corporation of Delaware

Application July 22, 1950, Serial No. 175,401

15 Claims.

(Cl. 242—75)

1

This invention relates to mechanism for conveniently handling long pieces of tape-like material, and more particularly to such a mechanism wherein any desired portion of the tape may be scanned at high speed.

It is an object of the invention to provide a tape-handling mechanism in which tape, which is normally stored on a spool in the same fashion as moving-picture film, may be removed from the storage spool and deposited on a take-up spool at very high speeds, with extremely high acceleration of motion and reversal of direction, without danger to the tape.

It is another object of the invention to provide such a mechanism wherein any portion of the tape may be examined while moving at a desired rate of speed, and the tape may be started from rest and brought to rest in a minimum time, smaller than would ordinarily be permitted in view of the weight of the spools and tape stored thereon.

To provide the foregoing and other features, the invention envisions a mechanism wherein an elongated tape, stored originally on a supply spool having substantial mass, is passed through a mechanism of low mass on which a certain amount of tape is removably stored, over a capstan, and thence to a similar storage mechanism to a take-up spool, the capstan being provided with means through which it can be rotated in either direction about its axis with extraordinarily great acceleration and deceleration. The low-mass tape-storage mechanism effectively isolates the capstan from the supply and take-up spools, so that the capstan can quickly accelerate the tape to a desired speed without endangering the same physically and can make a certain amount of the tape available for use at such speed during the time when the spools are being brought to desired supply and take-up speeds. The spools are brought to such speeds through the medium of motors which provide torques to the same, and the motors are controlled through the further medium of a sensing device which is operated by the low-mass storage mechanism, in such a manner that tape tension is at all times maintained substantially constant.

The invention as generally described above, and the foregoing and other features thereof which will presently appear, are particularly useful in the art of electronic computers, where it is now a practice to employ long magnetizable tapes in cooperation with magnetic recording heads as a means for storing information, for example, in a computing machine. Accordingly, a tape, which may be one thousand or more feet long and, for example, made of an acetate material

2

about one-half inch wide and quite thin, and having powdered magnetizable material deposited on one side thereof, is suitable for use as a storage medium for magnetically recorded information. Such a tape may have, for example, a tensile strength of five pounds, which is insufficient if a portion of it is to be accelerated at an extremely high rate against the inertia of a large spool bearing the larger portion of the tape.

Thus, in a particular computer, it is desirable to be able to examine a prescribed two-inch length of a one-thousand-foot tape, and to be able to accelerate the tape within one-eighth of an inch of linear travel from a standing position to a speed of thirty inches per second, and further to be able to reverse the direction of the tape in about three-eighths of an inch from a speed in one direction of thirty inches per second to a speed in the opposite direction of sixty inches per second.

It will be appreciated that these requirements would place a large strain upon a tape such as that described, having a tensile strength of only five pounds. An apparatus such as that which will be described below has been constructed which accomplishes these results while imposing negligible stresses in the tape.

Referring now to the accompanying drawing:

Fig. 1 illustrates a tape-handling mechanism constructed in accordance with the invention;

Fig. 2 illustrates one step in the operation of feeding tape into the slack-absorber mechanism of Fig. 1;

Fig. 3 illustrates a second step of the operation illustrated in Fig. 2;

Fig. 4 illustrates schematically an alternative system for driving the tape spools in Fig. 1;

Fig. 5 illustrates a control circuit for the motor of Fig. 4;

Fig. 6 illustrates an actual construction for supporting the system shown in Fig. 4;

Fig. 7 illustrates a capstan drive; and

Fig. 8 is an enlarged view showing the details of a magnetic clutch.

Referring now to Figs. 1, 2 and 3, a platform generally designated by the numeral 10 bears upon it a first tape spool 11, which may for convenience be termed the supply spool, and a second tape spool 12, which may for convenience be termed a take-up spool. Each spool is rotatably mounted upon the platform 10 about a mounting 13 or 14, respectively. The supply spool 11 is driven by a first motor 15, and the take-up spool 12 is driven by a second motor 16. The first motor 15 has an armature 17 which is connected to the supply spool 11 through a shaft 18, and the second motor 16 has an armature 19 which is connected to the take-up spool 12 through a

shaft 21. It will be appreciated that the armatures are, in each case, directly beneath their respective spools, and the shafts are actually perpendicularly disposed with relation to the spools, but these are illustrated in a single plane in Fig. 1 for the sake of simplicity. The first and second motors 15 and 16 are provided with field windings 22 and 23, respectively, which are energized in parallel from a suitable source of D. C., not shown, through field-current terminals 24, 25. As will be explained more in detail below, the motors provide to the spools 11 and 12 torques which tend to rotate them in opposite directions, as indicated by the arrows 26 and 27, respectively, shown thereon.

The platform 10 supports also a capstan 30 which is rotatably mounted thereon and driven through a shaft 31 from a continuously running motor 32. The continuously running motor drives a first gear 33 which is meshed with a second gear 34, and each of these gears drives a magnetic clutch 35 and 36, respectively. The magnetic clutches are of a design to be described more in detail below, and may each briefly be understood to consist essentially of a constantly rotating body which is affixed to the gear 33 or 34 and a second body, not shown in Fig. 1, which is affixed to a shaft 37 or 38, respectively. Each of the clutches may be so operated that its shaft 37 or 38 may be caused to rotate with its constantly rotating body 35 or 36, respectively, or disengaged therefrom and stopped at will, and the construction whereby this is accomplished will likewise appear below. The shaft 37 of clutch 35 is directly connected to the cross arm 39 of a differential gear arrangement 41. Bevel gears 42 and 43 are rotatably mounted one on each end of the cross arm 39. The shaft 38 of clutch 36 drives a gear 44 which engages another gear 46 which is rotatably disposed about the shaft 37 of clutch 35. Thus, shaft 37 and gear 46 may be rotated coaxially in the same or opposite directions. Gear 46 is connected through a short tubular collar 47 to a gear 48 which is in mesh with both bevel gears 42 and 43 of the cross arm 39. A further gear 49 is in mesh with the cross-arm gears 42 and 43 at the opposite sides thereof from gear 48, and completes the differential gear arrangement 41. The shaft 31 which is connected to the capstan 30 is connected to and rotated by bevel gear 49.

It will be appreciated again that the shaft 31 is actually disposed perpendicular to the plane of the paper in Fig. 1 but is illustrated as lying in the same plane for the sake of simplicity. The capstan may be rotated in either direction by the shaft 31 by engaging one of the clutches 35 or 36 and disengaging the other clutch. Thus, assuming that the motor 32 is running continuously in a first direction in which the teeth of gear 33 which are visible appear to be moving from left to right, as indicated by the arrow 33' in Fig. 1, and the clutch 35 is energized to drive shaft 37 while clutch 36 is de-energized and shaft 38 is stationary, then the cross arm 39 is being rotated in the same direction as gear 33 while gear 46 and bevel gear 48 are stationary. Under these conditions bevel gear 49 rotates in the same direction as shaft 37 at twice the speed of shaft 37. On the other hand, if clutch 35 is de-energized, leaving shaft 37 stationary, and clutch 36 is energized, then, remembering that gear 34 is being rotated in a direction reverse to that of gear 33, gear 44 rotates in the same direction as gear 34, rotating gear 46 in the same direction

as gear 33. Now, with cross arm 39 and shaft 37 stationary, and gear 46 rotating in the same direction as gear 33, bevel gear 48, through cross-arm gears 42 and 43, rotates gear 49 in the same direction as gear 34. Gears 33 and 34 have the same number of teeth, and gears 44 and 46 have the same number of teeth, so that gear 49 rotates at the same speed as gear 33 or 34. All the bevel gears 42, 43, 48 and 49 of differential 41 have, of course, the same number of teeth. Thus, gear 49, and with it shaft 31 and capstan 30, can be driven in either of two possible directions, in one of which directions the speed is double the speed of the other direction.

The tape 50 which is stored on spools 11 and 12 passes over the capstan 30 and is driven from one spool to the other by the capstan. As has been previously mentioned, the motors 15 and 16 rotate the spools 11 and 12 in opposite directions, so that, the tape being wound in opposite directions thereon, the tape is maintained under a predetermined amount of tension and can be driven frictionally by the capstan 30 from one spool to the other. To absorb slack in the tape 50 between the capstan and each of the spools, a slack-absorber mechanism 51 is included. This mechanism includes a generally vertically disposed slack-absorber bar 52 having a plurality of rectangularly extending arms 53, 54, 55, 56, 57 and 58 mounted thereon. Arms 53, 55 and 57 extend from one side of bar 52, while arms 54, 56 and 58 extend from the other side thereof. The arms extending from each side are alternately arrayed along the bar, so that the uppermost arm 53, extending to the left in Fig. 1, is succeeded by the first arm 54 of those extending to the right in Fig. 1, and then by the second arm 55 of those extending from the left, etc. The material of the bar and arms is maintained at a minimum, to minimize the weight thereof, by removing excess material and leaving apertures 59 in place of the excess material. At the extreme end of each arm 53 to 58, inclusive, there is rotatably mounted a tape-engaging pulley, the pulleys of the left-hand arms being generally designated by the reference numeral 61, and the pulleys on the right-hand arms being generally designated by the reference numeral 62. The bar 52 is provided at its top with a cross member 63 which is of hollow tubular form and is slidably fitted over a slide bar 64. The slide bar 64 is supported at its ends in standards 65 and 66, which are mounted on the platform 10, so that the bar 52 can be slid back and forth between the standards 65 and 66 over the platform 10 without substantial change in its generally vertical direction, as shown in Fig. 1. Two additional tape-engaging pulleys 67 and 68 are rotatably mounted on the platform 10 in a vertical line which is displaced to the left from the line of the left-arm pulleys 61 and parallel thereto, with pulley 67 intermediate the upper two left-arm pulleys 61 and pulley 68 intermediate the lower two left-arm pulleys 61. Four additional tape-engaging pulleys 70, 71, 72 and 73 are rotatably mounted on the platform 10, arrayed in a vertical line parallel to the line of the right-arm pulley 62 and displaced to the right thereof, as shown in Fig. 1. Pulley 71 is intermediate the upper two right-arm pulleys 62, and pulley 72 is intermediate the lower two right-arm pulleys 62. The topmost and lowermost pulleys 70 and 73 of this group are idler pulleys. An additional idler pulley 74 to the left of the topmost

left-arm pulley 61 is also rotatably mounted on the platform 10.

Assuming that tape is being taken from the supply spool 11, the tape passes first over idler pulley 74 and then in zig-zag fashion over the topmost left-arm pulley 61 of the slack-absorber mechanism 51, pulley 67, intermediate left-arm pulley 61, pulley 68, lowermost left-arm pulley 61, then around the capstan 30 to idler pulley 73, then in zig-zag fashion over the lowermost right-arm pulley 62 of the slack-absorber mechanism 51, pulley 72 intermediate right-arm pulley 62, pulley 71, uppermost right-arm pulley 62, and then around idler pulley 70 and to the take-up spool 12.

The tape may be threaded upon the idler mechanism in a simple fashion, which is illustrated in Figs. 2 and 3, where the tape 50 is shown in dotted lines. Referring particularly to Fig. 2, the bar 52 is first displaced to the left close to the left-hand support 66 of the slide bar 64, so that the left-arm pulley 61 extends further to the left in Fig. 2 than the fixed pulleys 67 and 68. The virtue of the present construction now becomes apparent for the fixed pulleys 67 and 68 repose in Fig. 2 between left arms 53 and 55, and 55 and 57, respectively. With the slack-absorber mechanism in this position, the tape 50 is merely dropped or placed, without bending, to the right of the left-arm pulley 61 and simultaneously to the left of the fixed pulleys 67 and 68. Then, the slack-absorber bar 52 is displaced to its extreme right-hand position, nearest the right-hand support 66 of the slide bar 64, as is illustrated in Fig. 3. Automatically, this motion creates the zig-zag engagement of the tape 50 with the pulleys 61, 67 and 68, described above in connection with Fig. 1. Simultaneously, the portion of the tape 50 which is disposed between idler pulleys 70 and 73 can now be placed to the left of right-arm pulley 62 and to the right of fixed pulleys 71 and 72, whereupon return of the slack-absorber bar 52 to the intermediate position shown in Fig. 1 provides the two zig-zag slack tape configurations in Fig. 1.

Returning now to Fig. 1, it will be apparent that, with the tape-storage spools 11 and 12 provided with torques in opposite directions and the capstan 30 at rest, the slack-absorber mechanism 50 will tend to remain in a fixed position. As will be explained presently, the rest position of the slack-absorber bar 52 is generally half way between the extreme positions shown in Figs. 2 and 3. Upon acceleration of capstan 30 in a counterclockwise direction, for example, a certain amount of tape is removed from tape-engaging pulleys 61, 67 and 68 and the same amount of tape will be provided to pulleys 62, 70, 71, 72 and 73, causing the slack-absorber bar 52 to be displaced to the left in Fig. 1, thus providing effective isolation from the spools 11 and 12. The construction of the apparatus shown in Fig. 1 is such that the slack-absorber mechanism 51 has a great deal less inertia than the tape-storage spools 11 and 12 and the tape stored thereon, with the result that the slack-absorber bar 52 moves long before the inertia of the spool 11 or 12 from which tape is being taken can be overcome. Similarly, if the capstan 30 is accelerated from rest in a clockwise direction, slack tape is removed from pulleys 62, 70, 71, 72 and 73 and is supplied to pulleys 61, 67 and 68, causing the slack-absorber bar 52 to move to the right-hand position, as is illustrated in Fig. 3. In either case, the tension of the tape 50 remains

substantially undisturbed. A magnetic recording or scanning head, illustrated diagrammatically at 75, may be disposed adjacent a straight portion of the tape 50, near the capstan 30, for example, and scanning of the tape for information stored thereon, or for the purpose of storing information thereon, may be commenced immediately, without waiting for the spools 11 and 12 to be brought to full-operating speed. A sensing mechanism, generally designated as 76, cooperates with an electronic motor-control circuit, generally designated as 77, for the purpose of sensing the displacement of the slack-absorber bar due to acceleration in either direction 15 of the capstan 30, and adjusting the torques supplied between motors 15 and 16 to the spools 11 and 12, respectively, to restore the slack-absorber bar 52 to its intermediate, or rest, position before all the stored slack tape has been removed from one side of it, as will now be described.

The electronic circuit 77, which controls the motors 15 and 16, comprises a transformer 80 having a primary winding 81 supplied with input terminals 82 and 83, which are adapted to be connected to a source of alternating current. The secondary winding 84 of the transformer 80 is connected at one end to the anode 85 of a first grid-controlled gaseous-discharge tube 86 and at 20 the other end to the anode 87 of a second grid-controlled gaseous-discharge tube 88. The cathode 90 of the first gaseous-discharge tube is connected to one of the brushes 91 of the armature 17 of the first torque motor 15, while the cathode 92 of the second gaseous-discharge tube is connected to one of the brushes 93 of the armature 19 of the second torque motor 16. The remaining brushes 94 and 95 of the armatures 17 and 19, respectively, are connected together and 25 through a common conductor 96 to the center tap 97 of the secondary winding 84. Thus, a circuit through the first armature 17 is completed from the center tap 97 through the lower half of the secondary winding 84, as seen in Fig. 1, through 30 the anode-cathode path of the first gaseous-discharge tube 86 to brush 91, through the first torque-motor armature 17 and brush 94 to the common conductor 96. A similar circuit for the second torque-motor armature 19 may be traced 35 from the center tap 97 through the upper half of the secondary winding 84, as seen in Fig. 1, through the anode-cathode path of the second gaseous-discharge tube 88 to brush 93, then through the second torque-motor armature 19 to brush 95, and to the common conductor 96.

The sensing mechanism 76 is essentially an electrical phase-shifting device having input conductors 101 and 102 connected, respectively, to the input terminals 82 and 83. A first capacitor 103 and a first resistor 104 are connected in series from input conductor 102 to input conductor 101. A second capacitor 105 and a second resistor 106 are also connected in series from input conductor 101 to input conductor 102. A first movable tap 107 on the first resistor 104 is electrically connected to the control grid 108 of the first gaseous-discharge tube 86. A second movable tap 109 on the second resistor 106 is electrically connected to the control grid 111 of the second gaseous-discharge tube 88. Current-limiting resistors 112 and 113, respectively, are included in series in these connections. A first capacitor 114 is connected between the control grid 108 and the cathode 90 of the first gaseous-discharge tube 86, while a second capacitor 115

is connected between the control grid 111 and the cathode 92 of the second gaseous-discharge tube 88. A fixed bias may be provided between the cathode and control grid of each of the first and second gaseous-discharge tubes 86 and 88 by fixed-bias sources 116 and 117, respectively, if desired. The fixed-bias sources 116 and 117 may, for example, be batteries in series with suitable grid-return resistors.

The movable taps 107 and 109 are mechanically affixed to the opposite ends of elongated bar 120 which is pivotally mounted at an intermediate point 121 on the platform 10. An elongated arm 122 extends rectangularly from the bar 120 at the pivot point 121, downwardly as shown in Fig. 1, and is provided at its lower end with a slideway 123. A pin 124, which is mounted at the upper end of the slack-absorber bar 52, is engaged in the slideway 123. As is shown in Figs. 2 and 3, the slack-absorber bar 52 is operative, through the pin 124 and the slideway 123, to rotate the bar 120 bearing the taps 107 and 109 about the pivot point 121, in a direction depending upon the direction of displacement of the slack-absorber bar from its neutral or median position, which is shown in Fig. 1. Upon rotation of bar 120 clockwise about its pivot point 121, as is shown in Fig. 2, movable tap 107 moves along resistor 104 further away from the associated capacitor 103 and close to conductor 101, while movable tap 109 moves along resistor 106 closer, electrically, to the associated capacitor 105 and further away from conductor 102. This has the effect of causing one tube to fire later in its conductive half cycle and the other to fire earlier in its conductive half cycle. The sense of this change is the opposite when the bar 120 is rotated in the counterclockwise direction, as is shown in Fig. 3. The change in either case causes one of the motors 15 or 16 to furnish more torque to its shaft 18 or 21, respectively, and the other motor to furnish less torque to its shaft. In the case where the capstan 30 is accelerated in the counterclockwise direction, to remove tape 50 from spool 11, this change is employed to decrease the torque applied to the supply spool 11 in the direction of the arrow 26, and simultaneously to increase the torque applied to the take-up spool 12 in the direction of arrow 27. The sum of the torques is maintained substantially constant, so that the tension of the tape 50 will not be substantially changed. However, the difference between the individual torques is such that the slack-absorber bar 52 is returned toward its neutral or median position, shown in Fig. 1.

When the capstan 30 is accelerated in the clockwise direction, the slack-absorber bar 52 is quickly pulled toward its extreme right-hand position, as shown in Fig. 3. In this case, the firing times of the grids 108 and 111 are so altered that the torque applied to what is now the supply spool 12 in the direction of the arrow 27 is decreased, while simultaneously, the torque which is applied to what is now the take-up spool 11 in the direction of arrow 26 is increased. Again, the spools are caused to feed and take up the tape 50 sufficiently quickly to restore the slack-absorber bar 52 towards its neutral or median position.

If the capstan 30 has been accelerated to a desired speed, the slack-absorber bar 52 remains generally in its neutral or median position, and any drift away from that position is immediately sensed by the sensing mechanism 76 and corrected through the torque-motor control circuit

77. The tape is thus furnished at a desired constant speed, determined by the speed of the capstan 30, for scanning or recording upon by the head 75, for example. As has been pointed out above, the speed of the capstan in one direction is twice its speed in the other direction when the drive mechanism, which is illustrated in Fig. 1, is employed. With a mechanism in accordance with Fig. 1, it has been found that an acceleration in excess of 10,000 inches per second may be realized while tape stress is maintained below one pound.

Referring now to Figs. 4, 5 and 6, a modification of Fig. 1 is shown wherein an alternate spool-tensioning and control system is employed to control the tape spools 11 and 12. In this modification, the tape spools 11 and 12 are shown mounted upon splined hubs 130 and 131, respectively, which are collinearly arranged on coaxial shafts 132 and 133, respectively. It will be appreciated that the coaxial mounting of the spools 11 and 12 may be employed in the embodiment of Fig. 1, also, if desired. A first or control motor 134 and a second or tension motor 135 are employed to operate this arrangement. The control motor 134 turns a shaft 136 having a pinion gear 137 at the end thereof. The pinion gear 137 is in mesh with a large idler shaft gear 138 which turns an idler shaft 139 having a second pinion gear 140 at one end thereof. The second pinion gear 140 is in mesh with a large gear 141 which is mounted on and turns the shaft 132 on which tape spool 11 is mounted, and with an additional large gear 142 which is mounted on a hollow shaft 143 having one bevel gear 144 of a differential 145 at its end. The cross arm 146 of the differential 145, shown in Fig. 6, is mounted on a shaft 147 which is concentrically fitted within the hollow shaft 143 and extends a distance beyond it and carries a large gear 148. The tension motor 135 turns a shaft 149, at the end of which there is mounted a pinion gear 150 which is in mesh with the last-mentioned large gear 148. The shaft 147, which is turned by the tension motor 135 through gear 148 and pinion gear 150, turns the cross arm 146 of the differential 145 and with it the two cross-arm bevel gears 151 and 152. The cross-arm bevel gears are in mesh with the fourth gear 153 of the differential 145 which is mounted on a shaft 154 and turns a large gear 155. This large gear 155 is in mesh with a similar large gear 156 which is mounted on the hollow shaft 133 which carries the second tape spool 12.

As is shown in Fig. 6, shaft 147 is mounted at its ends at two opposite walls 158 and 159 of a rigid housing 160, and the motors 134 and 135 are mounted on the outside of wall 159. The shaft 136, which is driven by the control motor 134, is rotatably supported in a boss 161 which is firmly attached to wall 159, while the idler shaft 139 is also firmly supported in a portion of the base 162 of said boss. The shaft 149, which is turned by the tension motor 135, is also rotatably supported in a second boss 163 mounted on the same base 162 and supported firmly on the wall 159. The shafts 132 and 133 are rotatably supported in an external boss 164 which is mounted on wall 153 of the casing 168, and the splined hubs 130 and 131 project outwardly from this boss.

Referring again to Fig. 4 and assuming that the control motor turns its shaft 136 in the direction of arrow 165, which is counterclockwise in Fig. 4, then gear 138 and shaft 139 are turned

clockwise in the direction of arrow 166. The pinion 140 then causes gears 141 and 142 to be turned counterclockwise in the direction of arrows 167 and 168, so that shaft 133 and spool 11 are turned counterclockwise in the direction of arrow 169 on spool 11. Gear 142, turning counterclockwise as shown by arrow 167, rotates bevel gear 144 of the differential 145 in the same direction, and, if shaft 147 is at rest, causes gear 155 to be rotated at the same speed in the opposite or clockwise direction, as shown by arrow 171, on gear 155. However, the tension motor 135 has an effect on gear 155. Assuming that the motor is rotating shaft 149 in a clockwise direction, as indicated by arrow 172, then the pinion gear 150 thereof turns gear 148 in a counterclockwise direction, as indicated by arrow 173. The cross-arm shaft 147 then turns the cross-arm 146 of the differential 145 in the counterclockwise direction of arrow 173, and this causes shaft 154 to be turned in the same direction at double the speed of shaft 147, as indicated by arrow 174 on gear 155. The net effect of this is that gear 155 may be turned in either direction and, therefore, that the tape spool 12 may be turned in either direction, as indicated by arrows 175 and 176 thereon.

The power for driving the motors 134 and 135 is furnished by an arrangement somewhat different than that shown in Fig. 1. The tension motor 135 is excited by a constant voltage, from a source which is not shown, and the torque of this motor is maintained substantially fixed. The control motor 134 is, on the other hand, controlled both in speed and direction by a circuit similar to the control circuit 77 in Fig. 1. This circuit is, however, modified, as is shown in Fig. 5, where similar parts to those shown in the circuit 77 of Fig. 1 bear like reference numerals. The change consists essentially of placing the motor 134 in the common lead 96, which is attached at one end to the center tap 97 of the transformer winding 84, and removing the motor armatures 17 and 19, however without interrupting the current paths provided thereby. In this manner, employing the sensing device 76 of Fig. 1 to control the gaseous-discharge tubes 86 and 88 in the same manner as in Fig. 1, the speed and direction of the control motor 134 can be controlled.

Fig. 7 shows an actual construction for reversibly driving the capstan 30, similar to the construction which is schematically shown in Fig. 1. In these two figures, like parts bear like reference characters. In Fig. 7, however, the motor 32 drives an idler gear 201, and this gear in turn drives the gears 33 and 34 of the two magnetic clutches 35 and 36, respectively. The clutches are supported within a rigid casing 206 having a generally rectangular shape. The casing has two rectangular volumetric spaces 207 and 208 which are divided by a rigid partition 209. The motor 32 is mounted on the outside of a wall 205 of the casing, and the idler gear 201 is disposed inside space 207. The clutches 35 and 36 are disposed between walls 205 and 209, parallel to each other, and their output shafts 37 and 38, respectively, project into space 208 on the other side of dividing partition 209. Clutch 35 has a rotatable portion 202, on which gear 33 is affixed, and a nonrotatable portion 212 which is affixed to partition 209. Clutch 36 has a rotatable portion 203, on which gear 34 is rigidly mounted, and a nonrotatable portion 213 which is also affixed to partition 209.

The rotatable portion of each clutch is mounted on wall 205 of casing 206 by means of a bolt 204 which supports an antifriction ball bearing 215 in a manner which is shown clearly on clutch 36, where the rotatable portion 203 is partly broken away. The bolt 204 has an enlarged head 216 which cooperates with a sleeve 217 to compress the inner race of the ball bearing 215 between them when the nut 218 is tightened. The sleeve 217 rests upon a boss 219 on the inside of wall 205, and a washer 221 is disposed between the nut 218 and the outer surface of wall 205. The outer shell of rotatable member 203 has an annular groove in which a retainer ring 222 is held. An annular cap member 223 is bolted to the end of the outer shell of rotatable member 203 and retains the outer race of ball bearing 215 between the retaining ring and itself. The races are shown spaced away from their retaining members in Fig. 7 in order better to illustrate the disposition of the parts. As will appear below in connection with Fig. 8, the races are actually retained tightly in their desired positions. Gear 34 is bolted to the annular cap member 223 by means of bolts 225, being spaced therefrom by a spacer ring 226. A washer 227 of annular form is provided beneath the heads of the bolts 225. It will be appreciated that the rotatable member 203 of clutch 36 is freely rotatable upon the supporting bolt 204 and is driven through its drive gear 34. The construction of rotatable member 202 of the other magnetic clutch is identical.

Disposed between the fixed and rotatable members of each clutch is a clutch disk 230 which can be magnetically attracted to either member, as will presently be explained in connection with Fig. 8. The clutch disk is affixed to the shaft 37 or 38 of its clutch and turns the same when it is in contact with the rotatable member of the clutch, and holds the same stationary when it is in contact with the fixed member of the clutch. The shafts 37 and 38 drive, respectively, the cross arm 39 of differential 41 and gear 44. An idler gear 231 is included between gears 44 and 46 because of the inclusion of idler gear 201 between clutch gears 33 and 34. The differential gear 49, instead of driving directly the shaft 31, as it does in Fig. 1, drives a gear 232, which in turn drives another gear 233 on the shaft 31 of the capstan 30. It will be appreciated that the arrangement shown in Fig. 7 operates substantially in the same manner as Fig. 1 to drive the capstan in either of its two possible directions.

Referring now to Fig. 8, the construction of the magnetic clutches is shown in detail. The reference numerals correspond to reference numerals of clutch 36. The rotatable member 203 has an outer shell 235 in which the retainer ring 222 is supported. The head 216 of bolt 204 bears on the inner race of ball bearing 215. A plurality of shims 236 may be provided suitably to adjust the compression effected on the inner race when the bolt is tightened. A shoe 237, of annular form, which frictionally engages the clutch disk, is threaded on the outer shell 235. A first magnetizable piece 238 is affixed as by welding about an annulus 239 to the head 216 of bolt 204. A cooperating magnetizable piece 240 is retained on the first piece 238 by a retainer ring 241 which fits into an internal annular groove 242 in the cooperating piece and over an edge of the first magnetizable piece 238. An annular channel 243 is retained between the two magnetizable pieces 238 and 240, and a coil 244 is wound in this channel. Wires 245, 246 pass

through a passage 247 in the first magnetizable piece 238, and a cooperating passage 248 in the bolt 204, which is hollow, to the exterior of the clutch. The wires are in a fixed portion of the clutch, and, therefore, no rotation thereof will be encountered. The two magnetizable pieces 238 and 240 have pole surfaces 250 and 251 which are separated by a resilient ring 252.

The shaft 38 holds the clutch disk 230 splined thereon, so that the disk is slidable a short distance along the axis of the shaft, and the end of the shaft within the clutch is mounted in a recess 253 within the first magnetizable member 238. When the coil 244 of the rotatable member 203 is energized, the clutch disk 230, which is also made of magnetizable material, is attracted to the poles 250 and 251. The disk is provided with a first annular friction member 254, however, which engages the confronting surface 255 of the shoe 237 just prior to the disk 230 coming in contact with the poles 250 and 251. In this manner, the clutch disk is caused to rotate when the rotatable member 203, more particularly the outer shell 235, is rotated.

The fixed member 213 of the clutch is affixed to partition 209 by bolts 256. An outer magnetizable piece 257, of generally tubular form, has an outwardly-projecting flange 258 which threadedly engages the bolts 256. An inner magnetizable member, also of generally tubular shape, has an outwardly-projecting flange 260 through which the bolts 256 pass, which is compressed between the flange 258 of the outer magnetizable member and the partition 209 when the bolts are tightened. A generally annular channel member 261 is supported between the magnetizable members 257 and 259, and a coil 262 is disposed therein. Wires 263 and 264 are disposed in a passageway 265 through the inner magnetizable member 259 and a passageway 266 in partition 209. The magnetizable members 257 and 259 are, respectively, provided with pole surfaces 267 and 268 of annular form like the pole surfaces 250 and 251 of the rotatable member. Again, a resilient annulus 269 is retained between the poles. A shoe member 271 threadedly engages and fits over the outer magnetizable member 257.

When the coil 262 of the fixed clutch member is energized, the clutch disk 230 is attracted to the pole surfaces 267 and 268 thereof. The clutch disk is provided, however, with a second annular friction member, on the opposite side thereof from the first such member 254, and engages the confronting surface 273 of the shoe member 271 before the disk 230 itself can come in contact with the pole pieces 267 and 268. This effectively holds the shaft 38 rigid and nonrotatable when the fixed-member coil 262 is energized. When neither coil is energized, the shaft 38 is freely rotatable.

The arrangement of the hubs 11 and 12 collinearly, as shown in Fig. 4, contributes greatly to the ease with which the apparatus can be used. The splined hubs 130 and 131, shown in Fig. 6, are conveniently provided with identical splines and, in a manner well known in the art, with spring detents (not shown), so that the spools 11 and 12 may be of identical design, and may be simultaneously slipped over the hubs or removed from the same. In this manner, bearing in mind that the threading of the present apparatus is extremely simple and can be done with unlooped tape, a length of tape, which is disposed partially on one spool and partially on

the other, may be removed from or placed upon the mechanism with a minimum of effort at any time.

It will be appreciated by those skilled in the art that the foregoing detailed descriptions of particular means for carrying out the invention are exemplary only and that other modifications of the invention are possible. Accordingly, it is intended that the claims which follow shall not be limited by these details, which are illustrative only.

What is claimed is:

1. Tape-handling mechanism comprising a base, a first set of tape-engaging spools mounted in a first row on said base, a second set of tape-engaging spools mounted on said base in a second row parallel to said first row, a secondary base member having an elongated portion and a plurality of arms mounted thereon and extending alternately from opposite sides and substantially perpendicularly therefrom in a common plane, a tape-engaging spool mounted on each of said arms, and means on said base movably supporting said secondary base member with said elongated portion between and substantially parallel to said rows.

2. Tape-handling mechanism comprising a plane base, a first set of tape-engaging spools mounted in spaced-apart relation in a first row on said base, a second set of tape-engaging spools mounted in spaced-apart relation on said base in a second row parallel to said first row, a secondary base member having an elongated portion and arms mounted thereon and extending alternately from opposite sides and substantially perpendicularly therefrom in a common plane, a tape-engaging spool mounted on each of said arms, and means on said base movably supporting said secondary base member with said elongated portion between and substantially parallel to said rows and said common plane parallel to the plane of said base, the arms on one side of said elongated portion being disposed to extend between the spools of said first set when said elongated portion is displaced to be closely adjacent to said first row, and the arms on the other side of said elongated member being disposed to extend between the spools of said second set when said elongated member is displaced to be closely adjacent to said second row.

3. Mechanism in accordance with claim 2 wherein said mounting means comprises a tubular member mounted at one end of said elongated portion and disposed perpendicular thereto, an elongated bar slidably fitted within said tubular member, and means on said base supporting said bar parallel to said base and perpendicular to said rows.

4. Tape-handling mechanism comprising a plane base, a first set of tape-engaging spools mounted in spaced-apart relationship on said base, a second set of tape-engaging spools mounted in spaced-apart relationship on said base and separated from said first set, a secondary base member having an elongated portion and a plurality of arms mounted thereon and extending alternately from opposite sides and substantially perpendicularly therefrom in a common plane, a third set of tape-engaging spools mounted on said arms of the secondary base member, means on said base movably supporting said secondary base member with said third set between said first and second sets of spools, a tape supply spool and a tape take-up spool both mounted on said base, means to pro-

vide torque to each of said supply and take-up spools, means responsive to the displacement of said secondary base member from a prescribed position with relation to said base to alter said torques in opposite senses, a capstan mounted on said base for driving tape between said supply and take-up spools, means for rotating said capstan, and means for substantially instantaneously stopping the rotation of said capstan.

5. Tape-handling mechanism comprising a tape-supply means, a tape take-up means, a tape path extending between said means, a capstan, first slack-absorber means positioned in said tape path between said capstan and said supply means, said first slack-absorber means comprising a first tape-engaging spool with its axis of rotation movable with respect to the said supply means, second slack-absorber means positioned in said tape path between said capstan and said take-up means, said second absorber means comprising a second tape-engaging spool with its axis of rotation movable with respect to said take-up means, a rigid mechanical connection between the first and second slack-absorber means to effect a fixed relation between the displacements of the movable tape-engaging spools of the first and second slack-absorber means with respect to said supply and take-up means, motor means to drive said supply and take-up means, and means responsive to the relative displacement between the movable tape-engaging spools of said slack-absorber means and said supply and take-up means to cause said motor means to rotate said supply and take-up means to reduce the extent of said relative movement.

6. Tape-handling mechanism comprising a tape-supply means, a tape take-up means, a tape path extending between said means, a capstan, first slack-absorber means positioned in said tape path between said capstan and said supply means, said first slack-absorber means comprising a first tape-engaging spool with its axis of rotation movable with respect to the said supply means, second slack-absorber means positioned in said tape path between said capstan and said take-up means, said second absorber means comprising a second tape-engaging spool with its axis of rotation movable with respect to said take-up means, a rigid mechanical connection between the first and second slack-absorber means to effect a fixed relation between the movements of the movable tape-engaging spools of the first and second slack-absorber means with respect to the said supply and take-up means, torque-generator means connected to each of said supply and take-up means and arranged to supply opposing torques thereto, and means responsive to the relative movement between the movable tape-engaging spools of said slack-absorber means and said supply and take-up means to cause said torque-generator means to reduce the extent of said displacement.

7. Tape-handling mechanism comprising a tape supply means, a tape take-up means, a tape path extending between said means, a capstan, first slack-absorber means positioned in said tape path between said capstan and said supply means, said first slack-absorber means comprising a first tape-engaging spool with its axis of rotation movable with respect to the said supply means, second slack-absorber means positioned in said tape path between said capstan and said take-up means, said second absorber means comprising a second tape-engaging spool with its axis of rotation movable

with respect to said take-up means, a rigid mechanical connection between the first and second slack-absorber means to effect a fixed relation between the movements of the movable tape-engaging spools of the first and second slack-absorber means with respect to the said supply and take-up means, torque-generator means connected to each of said supply and take-up means and arranged to supply opposing torques thereto, and means responsive to the relative displacement between the movable tape-engaging spools of said slack-absorber means and said supply and take-up means to cause said torque-generator means to decrease the torque of said supply means and increase the torque of said take-up means to an extent sufficient substantially to nullify said displacement.

8. Tape-handling mechanism comprising a tape-supply means, a tape take-up means, a tape path extending between said means, a capstan, first slack-absorber means positioned in said tape path between said capstan and said supply means, said first slack-absorber means comprising a first tape-engaging spool with its axis of rotation movable with respect to the said supply means, second slack-absorber means positioned in said tape path between said capstan and said take-up means, said second absorber means comprising a second tape-engaging spool with its axis of rotation movable with respect to said take-up means, a rigid mechanical connection between the first and second slack-absorber means to effect a fixed relation between the displacements of the movable tape-engaging spools of the first and second slack-absorber means with respect to the said supply and take-up means, torque-generator means connected to supply and take-up means and arranged to supply opposing torques thereto, and means responsive to the relative displacement between the movable tape-engaging spools of said slack-absorber means and said supply and take-up means to cause said torque-generator means to reduce the extent of said displacement.

9. Tape-handling mechanism comprising a tape-supply means, a tape take-up means, a tape path extending between said means, a capstan, first slack-absorber means positioned in said tape path between said capstan and said supply means, said first slack-absorber means comprising a first tape-engaging spool with its axis of rotation movable with respect to said supply means, second slack-absorber means positioned in said tape path between said capstan and said take-up means, said second absorber means comprising a second tape-engaging spool with its axis of rotation movable with respect to said take-up means, and a rigid mechanical connection between the first and second slack-absorber means to effect a fixed relation between the displacements of the movable tape-engaging spools of the first and second slack-absorber means with respect to the supply and take-up means.

10. Tape-handling mechanism comprising a base, a first set of tape-engaging spools mounted in a first row on said base, a second set of tape-engaging spools mounted on said base in a second row parallel to said first row and separated from said first set, a secondary base member having an elongated portion and a plurality of substantially perpendicularly extending arms mounted thereon, a third set of tape-engaging spools each mounted on an arm of said secondary base member, means on said base movably support-

ing said secondary base member with said third set between said first and second sets of spools, a tape-supply spool and a tape take-up spool both mounted on said base, means to provide torque to each of said supply and take-up spools, and means responsive to the displacement of said secondary base member from a prescribed position with relation to said base to alter said torques in opposite senses.

11. Tape-handling mechanism comprising a base, a first set of tape-engaging spools mounted in a first row on said base, a second set of tape-engaging spools mounted on said base in a second row parallel to said first row and separated from said first set, a secondary base member having an elongated portion and a plurality of substantially perpendicularly extending arms mounted thereon, a third set of tape-engaging spools each mounted on an arm of said secondary base member, means on said base movably supporting said secondary base member with said third set between said first and second set of spools, a tape-supply spool and a tape take-up spool both mounted on said base, electric motor means to provide torque to each of said supply and take-up spools, and means having relatively movable members mounted in part on said base and in part on said secondary base member and responsive to the displacement of said secondary base member from a prescribed position with respect to said base to cause said motor means to alter said torques in opposite senses.

12. Tape-handling mechanism comprising a base, a first set of tape-engaging spools mounted in a first row on said base, a second set of tape-engaging spools mounted on said base in a second row parallel to said first row and separated from said first set, a secondary base member having an elongated portion and a plurality of substantially perpendicularly extending arms mounted thereon, a third set of tape-engaging spools each mounted on an arm of said secondary base member, means on said base movably supporting said secondary base member with said third set between said first and second sets of spools, a tape-supply spool and a tape take-up spool both mounted on said base, means to provide torque to each of said supply and take-up spools, means responsive to the displacement of said secondary base member from a prescribed position with respect to said base to alter said torques in opposite senses, a capstan mounted on said base for driving tape between said supply and take-up spools, and means for rotating said capstan.

13. Tape-handling mechanism comprising a base, a first set of tape-engaging spools mounted in a first row on said base, a second set of tape-engaging spools mounted on said base in a second row parallel to said first row and separated from said first set, a secondary base member having an elongated portion and a plurality of substantially perpendicularly extending arms mounted thereon, a third set of tape-engaging spools each mounted on an arm of said secondary base member, means on said base movably supporting said secondary base member with said third set between said first and second sets of spools, a tape-supply spool and a tape take-up spool both mounted on said base, means to provide torque to each of said supply and take-up spools, means responsive to the displacement of said secondary base member from a prescribed position with respect to said base to alter said

torque in opposite senses, a capstan mounted on said base for driving tape between said supply and take-up spools, means for rotating said capstan, and means for substantially instantaneously reversing the direction of rotation of said capstan.

14. Tape-handling mechanism according to claim 13 in which the capstan reversing means comprises first and second clutches each having a constantly rotating body and a nonrotating body, the nonrotating body having a longitudinal passage therethrough collinear with the axis of rotation of the rotating body, a shaft rotatably supported in said passage, and a clutch disk splined on the shaft movable between said bodies, said clutch disk being made of magnetizable material and the rotating and nonrotating bodies each having electromagnetic means to attract and hold the clutch disk, and clutch facings on the disk and each body of each clutch, means simultaneously to energize the electromagnetic means of the rotating body of one of said clutches and the electromagnetic means of the nonrotating body of the other of said clutches, and a driving connection between the shaft of each clutch and said capstan, said connections being arranged for driving said capstan in opposite directions from said constantly rotating bodies.

15. Tape-handling mechanism comprising a tape-supply spool, a tape take-up spool, a tape path extending between said means, a capstan, first slack-absorber means positioned in said tape path between said capstan and said supply means, said first slack-absorber means comprising a first tape-engaging spool with its axis of rotation movable with respect to the said supply means, second slack-absorber means positioned in said tape path between said capstan and said take-up means, said second absorber means comprising a second tape-engaging spool with its axis of rotation movable with respect to said take-up means, means to effect a fixed relation between the displacements of the movable tape-engaging spools of the first and second slack-absorber means with respect to said supply and take-up means, driving means for said supply and take-up spools comprising first and second coaxial shafts, first and second hubs supported collinearly by said first and second shafts, respectively, and means to provide torque to each of said shafts, and means responsive to the displacement of said movable tape-engaging spools of said slack-absorber means with respect to said supply and take-up means to alter said torque in opposite senses.

JOHN E. DE TURK.
